UNITED STATES PATENT OFFICE

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY

MACHINE FOR INSERTING FASTENINGS

Original application filed July 23, 1923, Serial No. 653,291. Divided and this application filed June 11, 1927. Serial No. 198,180.

This invention relates to machines for inserting fastenings, and is herein illustrated as embodied in a lasting machine of the progressive type including in its organization means for forming and driving staples to fasten the upper of a shoe in lasted position, this application being a division of a co-pending application Serial No. 653,291, filed on July 23, 1923. It is to be understood, however, that the invention is not limited to machines of the particular type herein shown.

A feature of the invention consists in a novel organization of means for forming a staple in one location and for transferring it to a different location for driving. In the machine herein shown each staple is driven into the shoe in a direction inclined to the vertical, and the staple is formed in a location above the path of the driver and is transferred downwardly into said path. An object thus in view in a machine of the type illustrated is to position the staple-forming means where it will afford ample room for the operation of the gripper that pulls the upper over the last and for manipulation of the shoe in presenting different portions of the upper in position for lasting. The transfer of the staple, in the construction shown, is effected by a portion of the staple-forming means, namely, an outside former which is moved forwardly with a staple-guiding nozzle from which the staple is thereafter driven, and which by that movement forms the staple over a stationary inside former.

Conveniently the outside former, as herein illustrated, is further utilized to guide the staple as it is moved forwardly by the driver in the driving operation, and to that end it is so constructed as to provide an unobstructed opening in the plane of the staple for the movement of the driver. As thus constructed, the outside former does not engage the head or cross-bar of the staple, but only those portions of the staple wire that form the legs of the staple. In order that this outside former shall not have to operate in such close relation to the sides of the inside former as to form the cross-bar solely by drawing action on the staple wire, for example in making a substantially straight cross-bar, with conse-

quent danger of weakening the staple at the junction of each leg with the cross-bar, the invention further provides a member separate from the outside former to co-operate with the inside former in forming the cross-bar, this member, as illustrated, being movable with the outside former in the staple-forming operation but not in the transferring operation.

It is desirable that the staple-guiding nozzle, which moves with the outside former, shall have sufficient range of movement to permit it to be retracted well away from the shoe at the time when the gripper begins its operation on the upper in lasting each portion of the shoe, and accordingly the construction shown is such that the outside former occupies initially a position at a substantial distance from the inside former. Preparatory to the forming of each staple the staple wire is fed into position between the formers, and the invention further provides novel means for guiding the wire and for maintaining it in position to be operated upon, the construction shown comprising a guide movable with the outside former as the latter approaches the inside former and having an elongated slot to permit it to move relatively to the wire while maintaining the wire in proper position.

The above and other features of the invention, including also novel means for guiding the staple in its transfer from forming position to driving position, novel means for operating and controlling the driver, and various novel details of construction and combinations of parts, will now be more particularly described with reference to the accompanying drawings and pointed out in the claims.

In the drawings,

Fig. 1 is a view in right-hand side elevation of the head portion of a machine in which the invention is embodied;

Fig. 2 is a view on a larger scale of a portion of the head of the machine, as viewed from the opposite side;

Fig. 3 is a perspective view of a portion of the staple-forming and driving means;

Fig. 4 is a perspective view showing in de-

tail parts of the staple-forming and driving means with staple wire fed into position for the forming of a staple;

Fig. 5 is a view similar to Fig. 4 showing the parts as they appear when the wire is about to be cut;

Figs. 6, 7 and 8 are sectional views of the inside and outside formers and associated parts, illustrating different stages of the staple-forming operation;

Fig. 9 is a view similar to Figs. 4 and 5, illustrating the positions of the parts after the staple has been transferred into alignment with the driver;

Fig. 10 is a perspective view showing one side portion of the outside former; and

Figs. 11 and 12 are views illustrating different positions of parts of the machine in operating upon a shoe.

As described in detail in the copending application referred to, the lasting machine in which the invention is herein shown as embodied comprises a stationary shoe rest 20 which, in operating upon shoes of the welt type, is adapted to engage the rib of the insole and to serve as a clinching member for the staples, a gripper 22 which is operated to pull the upper heightwise of the last and then inwardly over the margin or feather of the insole, and an overlaying member 24 comprising a staple-guiding nozzle which is moved in a direction inclined to the bottom face of the insole to lay the margin of the upper over the feather and against the rib and to hold it while a staple is driven by a driver 26 to fasten the upper to the rib, the legs of the staple being clinched on the inner face of the rib by the member 20, as illustrated in Figs. 11 and 12. The construction of the gripper and the means for operating it need not be described in detail, since they are fully described in the copending application.

In order to provide ample room for manipulation of the shoe and for the operation of the gripper, the staple-forming mechanism is so constructed and arranged as to form each staple in a location out of alignment with the staple driver 26 and above the path of movement of the driver, and there is provided means for transferring the staple downwardly into alignment with the driver between the staple-forming and the driving operations. For forming the staple there is provided an inside former 28 supported in a stationary bracket 30 secured to the frame of the machine, the former 28 having a cylindrical shank portion 32 adjustably secured in a recess in the bracket 30 by a set screw 34. The rest of the staple-forming mechanism, and the means for transferring the staple from forming position to driving position, with the exception of a portion of the wire-cutting means, are carried by a slide 36 which also carries the staple-guiding nozzle 24, this slide being mounted for reciprocating movement

in an inclined guideway 38 in the head of the machine. For reciprocating the slide 36 there is provided a lever 40 adjustably fulcrumed on the frame at 42 and having at its upper end a roll (not shown) engaged by a path cam 44 formed in a cam wheel 46 on a cam shaft 48 which is operated by means described in the copending application. The lower end of the lever 40 is yieldingly connected to a link 50 which is pivotally connected at 52 to the slide 36.

The outside former comprises two plates 54 secured to a slide bar 56 which is mounted for upward and downward movement in the slide 36 for a purpose hereinafter described, the plates 54 being arranged to co-operate with the inside former 28 to form a staple in response to the forward movement of the slide 36 whereby the staple nozzle 24 is carried into engagement with the shoe. Also carried by the slide 36 is a cutter 58 arranged to co-operate with a cutter 60 on the bracket 30 to cut the wire *w* in the forward movement of the slide 36. To position the wire in proper relation to the inside and outside formers there is provided a guide 62 which guides the wire across the end of the inside former 28 until its end engages an adjustable abutment 64 in the bracket 30, the guide 62 being fast on a portion of the staple nozzle 24. By reference to Fig. 6 it will be seen that initially the outside former 54 is positioned at a considerable distance from the inside former 28, thereby providing for an increased range of movement of the staple-guiding nozzle 24 toward the work, so that it may be positioned initially far enough from the shoe to avoid interference with the action of the gripper, and the guide 62, which moves with the outside former, has therein an elongated slot extending substantially from the inside former to the outside former to permit it to move relatively to the wire while maintaining the wire in proper position until it is engaged by the outside former. The guide member 62 is divided so that portions of it are positioned at opposite sides of the inside former. As soon as the outside former arrives in position to engage the wire, the cutters 58 and 60 operate to sever a length of wire proper for the forming of the staple, as illustrated in Fig. 7, and by the continued movement of the parts the section of wire is bent about the inside former, as illustrated in Fig. 8.

It will be seen that the two plates 54 of the outside former are separated from each other to provide an unobstructed opening between them in the plane of the staple, for a purpose hereinafter disclosed. The outside former thus does not engage that portion of the staple wire which forms the head or cross-bar of the staple, but only the portions which form the legs, and it is provided with grooves 66 to receive the wire and shape the legs against

the opposite sides of the inside former 28. These grooves are so formed relatively to the inside former as not to subject the wire to as great a strain as would be necessary if the drawing action of the formers thereon were alone depended upon to shape the cross-bar of the staple, in order to avoid weakening the staple at the junction of each leg with the cross-bar. For shaping the cross-bar 10 there is further provided a member 68 formed on the lower end of a plate 70 which is fixed on the front face of a casing 72 that forms a part of the housing for the slide bar 56. The member 68 extends into the space between 15 the outside former members 54, and moves with the outside former in the staple-forming operation so as to engage the cross-bar of the staple and shape it upon the inside former at the end of the forward movement of the outer 20 side former. As herein illustrated, the member 68 and the co-operating face of the inside former 28 are so shaped as to form a substantially straight cross-bar on the staple, although the invention is not limited to means 25 for forming a cross-bar of that shape.

After the slide 36 has completed its forward movement and the staple has been formed as illustrated in Fig. 8, the staple is carried by the outside former downwardly 30 into the path of movement of the staple driver 26. For guiding the staple in its transferring movement there is provided a guide member 74 which is moved forwardly with the staple nozzle 24 and the wire guide 62 in 35 the staple-forming operation until one edge thereof is in alinement with the cross-bar forming face of the inside former 28. The guide member 74 is shaped similarly to the inside former, and thus guides the cross-bar 40 and the legs of the staple during its transferring movement, the legs of the staple lying in the grooves 66 of the outside former. In order to insure that the cross-bar of the staple will not catch upon the upper edge of the 45 member 74, this member is beveled at its upper end, as indicated at 76.

At the end of the downward movement of the outside former the staple is located below the lower end of the guide member 74 and 50 in the path of the driver 26, the arrangement being such that the lower end of the outside former embraces a bed member 78 of the driver guideway. The staple legs are thus confined in a space between the bed member 55 78 and shoulders 80 on the outside former above the grooves 66, and the driver 26 is guided in this space between the bed member 78 and the lower end of the guide member 74 and in the opening between the outside former 60 plates 54. The guideway thus provided for the staple and the driver is in alinement with a guideway 82 in the staple nozzle 24.

It will be understood that the transferring movement of the outside former is effected by 65 movement of the slide bar 56. In order to

position the outside former, at the opposite limits of its movement, in proper relation to the wire-guiding slot in the guide 62 and to the driver guideway respectively, there are provided adjustable stop screws 84 and 86 70 which are arranged to engage a lug 88 projecting from the slide bar 56, the stop screws being adjustably clamped in position and being adapted for use in setting up the machine and in compensating for any wear that may take place. The downward movement of the slide bar 56 is effected by a cam 90 (Fig. 2) on the cam shaft 48 through connections comprising a bell-crank lever 92 pivoted at 94 on the head of the machine and a link 96 which connects the bell-crank lever to a lug 98 on the slide bar 56, the lever 92 being provided with a roll 100 for engagement with the cam. The lever 92 is yieldingly connected to the link 96 through a spring 102 which bears at 85 one end on the lever and at the other end on a sleeve 104 threaded in a lug 106 on the upper end of the link 96. Extending through the spring 102 is a rod 108 which is pivotally connected at its upper end to the lever 92 and is slidably mounted in the sleeve 104, this rod having fast on its lower end a collar 110 which engages the lower end of the sleeve to provide a connection whereby upward movement is imparted to the slide bar 56 by the lever 92. 90 This upward movement is yieldingly effected through a spring 112 (Fig. 1) which acts on the lever 92 to force the roll 100 toward the cam 90. It will thus be seen that both the upward and downward movements of the outside former are effected by yieldable means, so that the stop screws 84 and 86 may determine the limits of movement of the former. 95

For operating the staple driver 26 there is provided a bell-crank lever 114 which is pivoted on an extension of the slide 36 and has clamped in a downwardly extending arm thereof a bar 116 the lower end of which is swiveled in a bearing in a block 118 mounted for upward and downward sliding movements in a driver bar 120 to which is secured the staple driver 26. The lever 114 is operated to impart staple-driving movement to the driver 26 by a torsion spring 122. For swinging the lever 114 against the resistance 100 of the spring 122 to retract the staple driver, there is provided means for depressing a forwardly extending arm of the lever, comprising a link 124 which is pivotally connected at 126 to a slide 128, this slide being connected to another slide 130 which is vertically reciprocated by a crank 132 on the front end of the shaft 48. At its lower end the link 124 carries a plate 134 positioned at the rear of a plate 136 mounted on the front end of 115 the forwardly extending arm of the lever 114, and the plate 134 is provided with a shoulder 138 which is arranged to engage the upper edge of the plate 136 to impart to the lever 114 its driver-retracting movement. A 120 125 130

spring 140 tends to swing the link 124 forwardly and thus to hold the plate 134 against the plate 136. It will thus be seen that retractive movement of the staple driver is effected by downward movement of the link 124. In order to cause the driver to drive the staple there is provided means for disengaging the shoulder 138 of the plate 134 from the upper edge of the plate 136, thereby releasing the lever 114 to the action of its spring 122. For this purpose the link 124 carries a cam member 142 which is arranged to engage a stationary cam member 144 on an arm 146 which is fast on the head of the machine. For limiting movement of the lever 114, the slide 36 has thereon a projection 148 in which is adjustably threaded a plug 150 which has therein a fibre disk 152 in position to be engaged by a boss 154 on the lever 114.

The means for feeding the staple wire may be of any suitable construction. As herein illustrated, there are provided feed rolls 156 and 158 to which the wire is fed from a reel (not shown), the roll 158 being yieldingly pressed toward the roll 156 by a spring 160.

For operating the feed rolls there is provided pawl and ratchet mechanism 162, 164 operated by a rocker arm 166 yieldingly connected by a spring 168 to a rock shaft 170. A rock shaft 170 is operated by a cam 171 at the lower end of a vertical shaft 172 which is connected by a gearing 174 to the shaft 48. After the wire leaves the feed rolls 156, 158 it passes through a guide tube 176 by which it is directed to a guide block 178 fast on the bracket 30. From the block 178 the wire passes into the slot formed in the guide 62 and across the rear face of the inside former 28 until it engages the limiting stop 64.

In the operation of the machine, briefly summarized, the shoe is presented with the rib of the insole in engagement with the staple-clinching member 20 in each location where a lasting operation is to be performed, and the upper is gripped and pulled by the gripper 22 in the manner described in the copending application. Before the upper is released by the gripper its margin is laid inwardly over the feather of the insole and against the rib by the action of the staple nozzle 24 which is advanced by a forward movement of the slide 36. By this forward movement of the slide 36 the outside former 54 and the cross-bar-forming member 68 are carried forwardly toward the inside former 28, and after a movement of the slide corresponding to the distance between the outside former and the inside former the cutters 58 and 60 act on the staple wire previously fed into position in the guide 62 to cut therefrom a section of wire of proper length for a staple. By continued movement of the slide 36 the outside former acts to bend the wire about the inside former and thereby to form the legs of the staple, and at the end of such move-

ment the member 68 engages the cross-bar of the staple to shape it against the inside former. By this forward movement of the slide the guide member 74 is advanced until its rear edge is in alignment with the cross-bar-forming face of the inside former. After the slide 36 has arrived at the end of its forward movement, the outside former 54 is moved downwardly by the lever 92 to carry the staple away from the cross-bar-forming member 68 and along the guide member 74 until it arrives in alignment with the staple driver 26. The outside former then remains at its lower limit of movement to guide the staple at the beginning of its driving movement. After the staple has arrived in alignment with the driver, which has been previously retracted by the action of the member 124, the driver-operating lever 114 is tripped and the driver is operated to drive the staple and to clinch its legs against the anvil member 20. Thereafter the parts are returned to their starting positions preparatory to the forming and the driving of another staple in the next location on the shoe where a lasting operation is to be performed.

Having described the invention, what I claim as new and desire to secure by Letters Patent of the United States is:—

1. In a machine of the class described, the combination with a staple driver movable in a direction at an angle to the vertical to drive a staple, of means for forming staples in a location above the path of their driving movement, a portion of said forming means being movable to transfer each staple separately downward into said path. 95

2. In a machine of the class described, the combination with a staple driver movable in a direction at an angle to the vertical to drive a staple, of an inside former and an outside former relatively movable to form a staple in a location out of alignment with the driver above the line of drive, said outside former being movable to transfer the staple downwardly into alignment with the driver. 105

3. In a machine of the class described, the combination with a staple driver movable in a direction at an angle to the vertical to drive a staple, of an inside former above the path of movement of the driver, and an outside former movable in a direction substantially parallel to the direction of the operative movement of the driver to form a staple over the inside former and then downwardly to transfer the staple into alignment with the driver. 115

4. In a machine of the class described, the combination with work-positioning means, of a staple-guiding nozzle movable toward the work, inside and outside formers, one movable with said nozzle and the other stationary, for forming a staple as the nozzle is moved toward the work, and means for imparting to one of said formers a movement to transfer 125

- the staple from forming position into position to be driven from said nozzle.
5. In a machine of the class described, the combination with work-positioning means, of 5 a staple-guiding nozzle movable toward the work and having a staple-guiding passage therein, inside and outside formers, one movable with said nozzle and the other stationary, for forming a staple in a position out of alinement with said passage as the nozzle is moved toward the work, and means for imparting to said movable former after the nozzle has arrived at the limit of its movement toward the work a movement to transfer the staple into alinement with said passage.
6. In a machine of the class described, the combination with work-positioning means, of 10 a slide movable toward the work, a staple-guiding nozzle carried by said slide and having a staple-guiding passage therein, means operative in response to the movement of said slide toward the work to form a staple in a position out of alinement with said passage, and mechanism for operating a portion of the 15 staple-forming means to transfer the staple into alinement with said passage.
7. In a machine of the class described, the combination with work-positioning means, of 20 a slide movable toward the work, a staple-guiding nozzle carried by said slide and having a staple-guiding passage therein, an inside former mounted independently of said slide, an outside former carried by the slide for forming a staple over the inside former 25 in a position out of alinement with said staple-guiding passage, and means for operating said outside former to transfer the staple into alinement with said passage.
8. In a machine of the class described, the 30 combination with a staple driver, of an inside former and an outside former relatively movable to form a staple in a location out of alinement with said driver, and a member arranged to co-operate with the inside former 35 to shape the cross-bar of the staple, the outside former being movable relatively to said member to transfer the staple into alinement with the driver.
9. In a machine of the class described, the 40 combination with a staple driver, of an inside former, an outside former movable to bend a section of staple wire about the inside former in a location out of alinement with the driver, and a member movable with said outside former 45 to shape the cross-bar of the staple, the outside former being further movable to carry the staple away from said member and into alinement with the driver.
10. In a machine of the class described, the 50 combination with a staple driver, of an inside former and an outside former relatively movable to bend a section of staple wire about the inside former, and a member arranged to co-operate with the inside former to shape 55 the cross-bar of the staple, the outside former being movable after the staple-forming operation to carry the staple away from said member prior to the operation of the driver on the staple.
11. In a machine of the class described, the combination with a staple driver, of an inside former and an outside former relatively movable to bend a section of staple material about the inside former to form the legs of a staple, and a member mounted independently of the outside former and arranged to shape the cross-bar of the staple upon the inside former substantially at the end of the relative movement of said formers to form the staple legs.
12. In a machine of the class described, an inside former and an outside former relatively movable to bend a section of staple material about the inside former, and a member for shaping the cross-bar of the staple upon the inside former, said member and the outside former being relatively movable after the staple-forming operation to separate the cross-bar of the staple from said member.
13. In a machine of the class described, the combination with a staple driver, of means for forming a staple in a location out of alinement with said driver, a portion of said staple-forming means being movable to transfer the staple into alinement with the driver, and means for guiding the staple during the transfer.
14. In a machine of the class described, the combination with a staple driver, of an inside former and an outside former relatively movable to form a staple in a location out of alinement with said driver, said outside former being movable to transfer the staple into alinement with the driver, and a member shaped similarly to the inside former for guiding the staple during the transfer.
15. In a machine of the class described, the combination with staple-driving means, of means for forming a staple and for thereafter transferring it from forming position into a different position for driving, and a member movable in the staple-forming operation into position to guide the staple during its transfer.
16. In a machine of the class described, the combination with staple-driving means, of an inside former, an outside former movable to form a staple over the inside former and movable thereafter to transfer the staple from forming position into a different position for driving, and a member movable with the outside former in the staple-forming operation into a position adjacent to the inside former for guiding the staple during its transfer.
17. In a machine of the class described, staple-forming means comprising inside and outside formers one of which is movable relatively to the other to form a staple, means for feeding staple wire into position to be op-

erated upon by said formers, the movable former being arranged to move a substantial distance toward the other former prior to its staple-forming action on the wire, and a guide for the wire arranged to move with said movable former to maintain the wire in position to be operated upon.

18. In a machine of the class described, staple-forming means comprising an inside former and an outside former movable relatively to the inside former to form a staple, means for feeding staple wire into position to be operated upon by said formers, the outside former being arranged to move a substantial distance toward the inside former prior to its staple-forming action on the wire, and a guide for the wire movable with the outside former and having a slot so arranged as to permit it to move relatively to the wire while maintaining the wire in position to be operated upon.

19. In a machine of the class described, the combination with work-positioning means, of a staple-guiding nozzle movable toward the work, means for driving a staple from said nozzle into the work, staple-forming means comprising a stationary former and a co-operating former movable with the staple nozzle to form a staple, the movable former being arranged to occupy initially a position at a substantial distance from the other former to increase the range of movement of the staple nozzle, means for feeding staple wire into position to be operated upon by the formers, and a guide for the wire arranged to move with the movable former and having a slot to permit it to move relatively to the wire while maintaining the wire in position to be operated upon.

20. In a machine of the class described, the combination with staple-driving means, of an inside former, an outside former movable to form a staple over the inside former and movable thereafter to transfer the staple from forming position into a different position for driving, means for feeding staple wire into position to be operated upon by the formers, a guide for the wire movable with the outside former while maintaining the wire in position to be operated upon, and a member also movable with the outside former into position to guide the staple during its transfer.

21. In a machine of the class described, the combination with work-positioning means, of a nozzle for guiding fastenings, a slide movable to carry said nozzle toward the work, a driver on said slide, a spring carried by said slide for operating the driver, and means operative independently of the movement of the slide to tension said spring.

22. In a machine of the class described, the combination with work-positioning means, of a nozzle for guiding fastenings, a slide movable to carry said nozzle toward the work,

a driver on said slide, a lever carried by said slide for operating the driver, a spring for operating said lever, and means for tripping said spring after the slide has arrived at the limit of its movement toward the work.

23. In a machine of the class described, the combination with work-positioning means, of a staple-guiding nozzle, a slide movable to carry said nozzle toward the work, means operative in response to such movement of the slide to form a staple, a staple driver on the slide, and a spring carried by the slide for operating said driver.

24. In a machine of the class described, the combination with work-positioning means, of a staple-guiding nozzle, a slide movable to carry said nozzle toward the work, means operative in response to such movement of the slide to form a staple, a staple driver on the slide, a lever carried by the slide for operating said driver, and a spring also carried by the slide for operating said lever.

25. In a machine of the class described, the combination with work-positioning means, of a staple-guiding nozzle, a slide movable to carry said nozzle toward the work, means operative in response to such movement of the slide to form a staple, a staple driver on the slide, a spring carried by the slide for operating the driver, and means operative independently of the movement of the slide to retract the driver and tension said spring.

26. In a machine of the class described, the combination with work-positioning means, of a slide movable toward the work, a spring-operated staple driver on said slide, means also carried by said slide for forming a staple in a position out of alignment with the driver, mechanism for operating a portion of the staple-forming means to transfer the staple into alignment with the driver, and means for tripping the driver to render it operative to drive the staple.

In testimony whereof I have signed my name to this specification.

GEORGE GODDU.
